US00D935334S

(12) **United States Design Patent** (10) Patent No.: **US D935,334 S**
(45) Date of Patent: **** Nov. 9, 2021**

(54) **RADAR**

(71) Applicant: **THALES DMS FRANCE SAS**,
Elancourt (FR)
(72) Inventors: **Philippe Gaudillere**, Cerons (FR);
Pierre Bordes, Bruges (FR); **Richard**
Montigny, Pessac (FR)

(**) Term: **15 Years**

(21) Appl. No.: **35/509,116**

(22) Filed: **Feb. 27, 2020**

(80) **Hague Agreement Data**

Int. Filing Date: **Feb. 27, 2020**

Int. Reg. No.: **DM/207018**

Int. Reg. Date: **Feb. 27, 2020**

Int. Reg. Pub. Date: **Apr. 17, 2020**

(30) **Foreign Application Priority Data**

Oct. 1, 2019 (EM) 006954376

(51) LOC (13) Cl. **10-04**

(52) U.S. Cl.

USPC **D10/65**

(58) **Field of Classification Search**

USPC D10/65, 67, 80; D14/230, 242

See application file for complete search history.
